Munn & Co.
ATTORNEY

UNITED STATES PATENT OFFICE.

HARRY MADISON, OF COUNCIL BLUFFS, IOWA.

BATH SPRAY APPARATUS.

Application filed June 7, 1928. Serial No. 283,599.

My invention relates to shower bath sprays and an object of the invention is to provide a shower bath spray which is adjustable vertically to suit the convenience of the person using the same.

Further the invention provides a bath spray attachment arranged to be detachably supported from a shower bath curtain.

With the preceding and other objects 10 and advantages in mind, the invention consists in the novel combination of elements, constructions and arrangement of parts to be hereinafter specifically referred to, claimed and illustrated in the accompanying drawings, wherein:

Figure 1 is a vertical sectional view of a bath apparatus with my invention associated with the shower bath curtain thereof,

Figure 2 is a vertical sectional view of the 20 spray attachment and curtain,

Figure 3 is a horizontal sectional view on line 3—3 of Figure 2,

Figure 4 is a similar view taken on line 4—4 of Figure 2,

Figure 5 is a top plan view,

Figure 6 is a longitudinal sectional view of a modification of the invention, and

Figure 7 is a transverse section taken on line 7—7 of Figure 6.

Referring to the invention in detail a 30 longitudinally bowed horizontally arranged bar 5 is secured upon the inner face of a shower bath curtain 6, intermediate the ends of the latter, by means of a transverse rivet 35 or other suitable fastening 7.

For the purpose of holding a bath spray 8 for vertical adjustment along the curtain 6, a laterally disposed resilient U-shaped clamp 9 is attached to the bar 5 centrally of its ends by means of the fastening 7. The extremities 10 of the clamp are disposed in divergent relation to facilitate engagement and disengagement of the spray 8 from the clamp.

The spray 8 comprises a cylinder or tube 11 having its upper end closed by a cap 12 threadedly received thereon and having a lower open threaded end 13. A plurality of water compartments in the form of cylinders 14 of a greater diameter than the

cylinder 11 are received thereon and have inwardly directed annular flanges 15 at the ends thereof which hug the cylinder. The flanges of the opposed end of the cylinders 14 receive packing elements 21 therebetween 55 to provide liquid tight joints. The annular flange of the uppermost cylinder is opposed to the lower edge of the cap 12, while the lower annular flange of the lowermost cylinder is opposed to a retaining nut 16 threaded 60 upon the threaded end 13 of the cylinder 11. Each of the cylinders 14 is provided with longitudinally aligned outlet or spray openings 17 through which water from these cylinders is discharged. In order to conduct water from the cylinder 11 to the water compartments, the cylinder is provided with a plurality of vertically aligned graduated outlet openings 18. As illustrated in Figure 2, one of these outlet openings is provided for each water compartment and is located in transverse alignment with the opening 17. By the provision of the graduated openings 18 the force of the spray 70 from each of the compartments will be equalized. In other words, if these outlet openings were of the same size, the force of the water from the lower compartments would be relatively great, while the force of the water from the other compartments would 75 be negligible.

To supply water to the cylinder 11 a hose or flexible conduit 19^a having one end received on the open end 13 of the cylinder and its opposite end communicating with a faucet 19, is provided.

To guide the spray 8 in its vertical adjustment in the clamp, a guide loop 21^a is carried by the cap 12 at a point diametrically opposite the outlet openings and is slidably 90 received on a guide tape 22 extending vertically of the cover with its lower end interposed between the clamp 9 and bar 5 and anchored to the fastening 7. The tape is spaced from the curtain and extends a slight 95 distance above the spray and is provided with a button opening 23 for engagement with a laterally projecting button 24 carried by the curtain.

With the spray thus held by the clamp 100

and guide tape the spray will be guided in a true vertical direction while it is being adjusted. Should it be desired to detach the spray from the curtain, it is only necessary to detach the upper end of the guide tape from the button to permit the loop to be slipped therefrom.

In the modification disclosed in Figures 6 and 7, the water compartments are in the form of transversely bowed perforated plates 25 which are arranged in longitudinal alinement on the cylinder 11 and each of which overlies one of the outlet openings 18. These plates 25 are formed with marginal flanges 26 along their edges and ends, which extend towards the cylinder and are welded or otherwise secured thereto. In this form of the invention the lower or open end of the cylinder receives one end of the hose and is provided with a lateral bead 27 for holding the hose thereon.

What is claimed is:—

1. In a bath apparatus, a flexible curtain, a rigid element attached thereto intermediate its ends, a resilient clamp projecting laterally therefrom, and a perforated conduit supported for vertical adjustment in the clamp, and a slidable connection between the conduit and curtain.
2. In a bath apparatus, a flexible curtain, a rigid element attached thereto intermediate its ends, a resilient clamp projecting laterally therefrom, a perforated conduit supported for vertical adjustment in the clamp, a tape attached to the curtain and extending parallel to the conduit, and a loop carried by the conduit and slidable on the tape.
3. In a bath apparatus, a split resilient clamp for attachment to a vertical support, and a bath spray vertically adjustable in the clamp, and means for slidably connecting one end of the bath spray to the vertical support.
4. A bath apparatus, a bath curtain, a resilient clamp projecting laterally therefrom, a perforated conduit supported for vertical adjustment in the clamp and detachable therefrom, a guide extending vertically along the curtain above the clamp, and a loop carried by the conduit and slidable on the guide.
5. In a bath spray, a spray conduit having one end closed and provided with a plurality of outlet openings, perforated cylinders received on the conduit with their walls spaced from the latter and their ends closed to afford separate water pressure compartments along the length of the conduit, and threaded elements received on the ends of the conduit for holding the cylinders thereon.

Signed at Ute, in the county of Monona and State of Iowa, this 2 day of June, A. D. 1928.
